BAFFLE SHIELD

Filed Dec. 26, 1930

Howard E. Blood

Charles G. Hill

UNITED STATES PATENT OFFICE

HOWARD E. BLOOD, OF DETROIT, MICHIGAN, ASSIGNOR TO NORGE CORPORATION, OF DETROIT, MICHIGAN, A CORPORATION OF MICHIGAN

DESIGN FOR A BAFFLE SHIELD

Application filed December 28, 1930. Serial No. 38,126. Term of patent 3½ years.

To all whom it may concern:

Be it known that I, HOWARD E. BLOOD, a citizen of the United States, and a resident of the city of Detroit, in the county of Wayne and State of Michigan, have invented a new, original, and ornamental Design for a Baffle Shield or Similar Article, of which the following is the specification, reference being had to the accompanying drawings, forming a part thereof.

In the drawings:

I claim:

The ornamental design for a baffle shield, or similar article, as shown.

HOWARD E. BLOOD.
